UNITED STATES PATENT OFFICE.

WILLIAM LAY, OF SENECA, SOUTH CAROLINA.

WATER-MOTOR.

SPECIFICATION forming part of Letters Patent No. 244,628, dated July 19, 1881.

Application filed November 26, 1880. (Model.)

To all whom it may concern:

Be it known that I, WILLIAM LAY, of Seneca city, in the county of Oconee and State of South Carolina, have invented a new and Improved Water-Motor, of which the following is a specification.

The object of this invention is to provide a cheap, simple, and economical water-motor that can be operated with a small quantity and 10 but slight fall of water.

The invention is designed as an improvement on the water-motors for which Letters Patent No. 223,930 and No. 227,023 were issued to me January 27, 1880, and April 27, 1880, respectively; and it consists in doubling the number 15 of parallel arms and attached buckets; of novel devices for tipping the buckets and for preventing the too early discharge of water therefrom; of improved automatically-closing valves, 20 and of novel valve operating and regulating devices, all of which will be hereinafter described.

Figure 1 is a sectional side elevation on line *x x*, Fig. 2. Fig. 2 is a plan of the device. 25 Fig. 3 is a sectional end elevation on line *y y*, Fig. 2. Fig. 4 is an end elevation of the same. Fig. 5 is a perspective view of a valve.

Similar letters of reference indicate corresponding parts.

30 In the drawings, *A* represents the frame supporting the mechanism. *B B* are the pillow-blocks, secured upon the base of the frame *A*, and serving as supports for the rocking shafts *C C*, that are set in line with each other a suitable distance apart.

35 *D D* represent four parallel arms or beams, firmly fixed in pairs upon their respective shafts *C C*, each pair of arms *D D* carrying pivoted between their ends on transverse pivots *a* the buckets *E E*, on whose bottoms are secured the rearward-projecting plates or bars *b b*, that are designed to come in contact, on the downward stroke, with the triangular blocks *G*, which are secured on the base of the frame *A*, and thereby tip said buckets *E E* so that their contents may be discharged. In rear of the buckets *E E* rods *H H* are passed transversely through each end of each pair of arms *D D*, so that when a downward stroke is made 45 the tip of the said buckets *E E* is limited by the contact of the bars *b b* with the rods *H H*.

Premature escape of water from the descending buckets *E E* is prevented by the broad bars *c c*, that are secured across the ends of each pair of arms *D D* and serve as covers for the 55 lips of the buckets *E E*, and said covers *c c* also serve to retain the weight of the water at the extreme ends of the arms *D D* and in a position for quick discharge.

The shafts *C C* are of triangular cross-section, and are held in the pillow-blocks *B B* by means of their trunnions *d d*. Said shafts *C C* are provided with end flanges, *f*, projecting upward from their broad horizontal faces, and the arms *D D* are secured midway of their 60 lengths on the outside of these flanges *f* by bolts or other suitable fastenings.

Secured to the under sides of the arms *D D*, immediately beneath the shafts *C C*, are boxes *F* for the reception of ballast or weights *g*, that 70 may be disposed in such a manner as to contribute to the steady running of the machine.

The water-reservoir is represented at *I*, provided with ports *h h*, located above the buckets *E E*.

Beneath the ports *h h*, on the upright of the frame *A*, are pivoted the gravity-valves *L*, with their convex faces in contact with the corresponding concave seats about the ports *h h*. Said valves *L* are provided with openings *l* in 80 their faces corresponding with a port, *h*, and have two downward-projecting side lugs, *k*, through whose ends are passed the bolts *i i* that pivot them to the frame *A*, and from the inner edges of these lugs *k* arms *m* project inward at right angles, and have suspended from the extremities weights *n*, that serve by their gravity to swing said valves *L* inward, and thereby close them after each opening; and at the outer edges of these valves *L* are fixed 85 stops *n'*, that engage against the uprights of the frame *A* as the valves *L* are swung inward and prevent them from being moved past their seats. These valves *L* have their lugs *k* set sufficiently apart from each other to admit of 90 the passage between them of the buckets *E E* as the latter move up and down.

The valve-operating devices consist of the valve-levers *M*, that are pivoted by studs *o* on the upper edges of the arms *D D* midway of 95 their length, and are extended upward through slots *p* in the horizontal slide-bars *N*, which are

supported on rollers q , that revolve on pins q' projecting laterally from the frame A in such a position that their ends may be pushed in contact with the valves L to open the same by 5 the motion of the valve-levers M, which move with the arms D D. In this instance the said valve-levers M are longitudinally slotted from side to side, as shown at r , though these slots r may be dispensed with, and in lieu thereof 10 the pivoting-studs o be set in suitable slots in the arms D D.

The regulating devices consist of transverse crank-rods O, whose ends are journaled in the lugs s, that depend from the adjusting-bars P, 15 which are pivoted at t on the frame A, while the crank-pins of said rods O are engaged in the slots r of the valve-levers M. These crank-rods O serve as the fulcrums for the valve-levers M, and accordingly as they are elevated 20 or depressed is the throw of the said levers M and slide-bars N shortened or lengthened and the opening of the valves L made correspondingly partial or complete. These bars P are connected at their unpivoted ends by a cross 25 brace or bar, P', to the center of which is attached a cord, Q, that is passed upward over a pulley, Q', and has a weight on the other end. By pulling on this cord Q the adjusting-bars P and crank-rods O can be raised, and the 30 throw of the levers M be thereby shortened, with the result of diminishing the flow of water into the buckets E E. A suitable automatic 35 governor may be attached to the cord Q, if desired.

35 For the purpose of stopping the machine at any time, elbow-rods R are firmly attached to the crank-rods O, and are carried to within easy access of the operator. By pulling on these rods R the crank-pins u of the rods O—the fulcrums of the levers M—may be elevated so as 40 to limit the throw of the levers M and slide-bars N to such a degree that the latter will fail to move the valves L, and consequently the supply of water to the buckets E E will be cut off, and by the same means the openings of the 45 ports h h may be regulated to any desired degree.

The power of the machine is transferred to the crank-shaft S of the driving-wheel T by 50 pitmen U, that are pivoted on rods U', which pass transversely through the arms D D near one end thereof. The cranks S' S' of the crank-shaft S are set at right angles to each other, after the manner of cranks on locomotives, 55 whereby dead-centers are avoided.

The power may be transmitted from the driving-wheel T by belt and pulleys V W, as indicated in Fig. 1, or by any other well-known devices.

60 The buckets E E are constructed and arranged so as to secure the greatest economy in water and certainty in movement. Each bucket E to load is brought alternately close up to the

under face of a valve, L, and receives its load or supply of water without leak or spatter, and 65 the bars ee prevent all loss of water by spilling as said buckets E E descend. By the alternate filling and emptying of the alternate buckets E E the desired motion is given to the machine. 70

I do not strictly confine myself to the precise construction and parts herein shown, for I am aware that considerable modification may be made in both without departing from my invention. 75

Having thus fully described my invention, I claim as new and desire to secure by Letters Patent—

1. An improved water-motor, constructed as herein shown and described, consisting of the 80 flanged rocking shaft C C, pairs of parallel arms D D, carrying buckets E E, pivoted gravity-valves L, slotted valve-levers M, slide-bars N, and fulcrum crank-rods O, arranged and adapted to operate as set forth. 85

2. In a water-motor, the combination, with the arms D D and buckets E E, of the bars c c, substantially as herein shown and described, whereby the water is prevented from escaping from the descending buckets, as set forth. 90

3. The combination, with the buckets E E, provided with plates b b, of the blocks G, substantially as herein shown and described, whereby the said buckets are tipped, as set forth. 95

4. The combination, with the arms D D and buckets E E, provided with plates b b, of the rods H H, substantially as herein shown and described, whereby the tipping of the buckets is limited, as set forth. 100

5. In a water-motor, the combination, with the water-reservoir I, of the pivoted valves L, provided with arms m and attached weights n, substantially as herein shown, and for the purpose specified. 105

6. In a water-motor, the combination, with the valve L and the arms D D, provided with studs o, of the valve-levers M and slotted slide-bars N, substantially as herein shown and described, whereby the valves are opened, as set forth. 110

7. In a water-motor, the combination, with the valve L, the slotted valve-levers M, and slotted slide-bars N, of the pivoted adjusting-bars P and fulcrum crank-rods O, substantially as and for the purpose described. 115

8. In a water-motor, the combination, with the valve L, the slotted valve-levers M, bars N, and fulcrum crank-rods O, of the rods R, substantially as herein shown and described, whereby the machine may be regulated as set forth. 120
